AMALGAMATING CYLINDER

Edwin L. Foster, Long Beach, Calif.

Application April 29, 1936, Serial No. 77,059

4 Claims. (Cl. 209—61)

This invention relates broadly to amalgamators and has for its object to provide an improved amalgamating cylinder.

In accordance with the present invention provision is made whereby a fresh, clean coat of amalgam or mercury is maintained on the face or periphery of the roller at all times and while in operation, thereby improving materially a device of this character, since heretofore after the amalgam plate or cylinder was used a short time it became dirty and dead, and without sufficient clean amalgam to contact the gold for any useful purpose.

The present invention together with its objects and advantages will be best understood from a study of the following description taken in connection with the accompanying drawings wherein:

Figure 1 is an elevational view of an amalgamating cylinder for use in an amalgamator, and in horizontal position.

Figure 2 is a longitudinal sectional view through the cylinder.

Figure 3 is an end elevational view thereof.

Figure 4 is a transverse sectional view through the cylinder.

Figure 5 is a fragmentary detail sectional view illustrating certain details hereinafter more fully referred to.

Figure 6 is a fragmentary detail sectional view showing the manner of securing one end of the spirally wound wire.

Figure 7 is an elevational view of an amalgamating cylinder for use in a vertical position.

Figure 8 is a longitudinal sectional view through the vertical amalgamating cylinder.

Figure 9 is a plan view of the vertical amalgamating cylinder, and

Figure 10 is a sectional view taken substantially on the line 10—10 of Fig. 8.

Referring to the drawings by reference numerals it will be seen that in each form thereof the amalgamating cylinder comprises a hollow cylindrical body 5 formed of suitable material and having welded or otherwise secured within its respective opposite ends plates or disks 6.

The plates or disks 6 have formed integral therewith pintles 7 adapted to be journaled in suitable bearings provided therefor in the amalgamator (not shown).

Further in each form of the invention there is spirally wound on the periphery of the cylinder 5 a wire 8 the respective opposite ends of which are anchored to the cylinder through the medium 55 of screws or similar fastening elements 9. The

wire 8 is for the purpose of spreading over the periphery of the roller the mercury contents 10 thereof.

The roller illustrated in Figures 1 to 6 inclusive is of a type particularly designed for use in the amalgamator in a horizontal position, and may be, and preferably is, mounted for revolving movement in the amalgamator.

This horizontally used amalgamating cylinder is provided in one of the end plates 6 with a filling opening normally closed through the medium 10 of a plug 11.

Also the horizontal amalgamating cylinder is adapted to contain therein the mercury 10, and from the interior of the cylinder the mercury 15 or amalgam, which latter is preferably composed of mercury and approximately two percent of cyanide is directed onto the periphery of the roller through tubes 11' arranged within the cylinder as shown and having one end fitting in suitable openings provided therefor in the periphery of the cylinder.

From the above it will be apparent that as the mercury issues through the tubes 11' onto the periphery of the cylinder the mercury will be caused to spread over the periphery of the cylinder through the medium of the spirally wound wire 8 which latter is preferably German silver wire.

From the above then it will be apparent that 30 in operation there is being continuously applied to the surface of the cylinder a fresh, clean coat of mercury or amalgam for use in separating or amalgamating metals, as gold, silver and copper, from their ores.

In the amalgamating cylinder shown in Figures 7 to 10 inclusive and which is designed for vertical disposition within an amalgamator a departure is made from the structure and assembly of the horizontal cylinder in that, in the vertical amalgamating cylinder there are provided at the respective opposite ends of said cylinder partition plates 12 which with the end plates 6 form chambers which receive the mercury 10 as shown in Figure 8, the mercury being 40 introduced into these chambers through passages provided in the spindles 7 and from feed boxes 13 provided on the free ends of the spindles and being preferably integral with the spindles.

Each feed box 13 is provided with a filling 50 opening equipped with a suitable screw plug 14 as shown.

Also in the periphery of the vertical cylinder there is provided for each of the mercury chambers a series of drilled holes 14 through which 55

the mercury issues onto the periphery of the cylinder to be spread throughout the length of the cylinder by the spirally wound wire 8 as is thought to be apparent.

5. It will be understood that in regard to the vertical cylinder the same may be mounted either for rotating movement or may be mounted stationary within the amalgamating device as found desirable.

10. It will be further appreciated that in either form of the invention the periphery of the cylinder will continuously present a fresh, clean coat of amalgam or mercury for contacting the amalgamable metals thus rendering the cylinder 15 highly efficient and substantially self-cleaning.

Having thus described the invention what is claimed as new is:

1. An amalgamating cylinder having a perforated perimeter and adapted to contain mercury 20 for issuance through the perforations in the cylinder, and a spreader element in spiral form disposed about the cylinder for spreading the mercury over the perimeter of the cylinder as the mercury issues from the latter.

25. 2. For use in an amalgamator, a cylinder having provision in the interior thereof for containing mercury, and also having perforations in the periphery thereof through which the mercury

issues to spread over the periphery of the cylinder, and a wire for spreading the mercury over the cylinder spirally wound about the cylinder and anchored at its respective opposite ends to the cylinder.

3. For horizontal disposition within an amalgamator, an amalgamating cylinder adapted to contain mercury and having interiorly thereof tubes one end of which are disposed in openings in the periphery of the cylinder, said tubes 10 serving to direct the mercury contents of the cylinder onto the periphery of the latter, and means spirally disposed about the periphery of the cylinder for spreading the mercury over the periphery of the cylinder as it issues onto the 15 periphery of the cylinder.

4. For vertical disposition within an amalgamator, an amalgamating cylinder having in the respective opposite ends thereof mercury containing chambers, and also provided in the periphery thereof with perforations through which the mercury issues onto the periphery of the cylinder from said chambers, and a spreading member spirally disposed about the periphery of the cylinder for spreading the mercury over 20 the periphery of the cylinder as it issues thereonto.
